VENEREAL PROPHYLACTIC

Sewell M. Corbett, Fort Bragg, N. C.

No Drawing. Application November 23, 1933,
Serial No. 699,431

3 Claims. (Cl. 167—58)

(Granted under the act of March 3, 1883, as
amended April 30, 1928; 370 O. G. 757)

This invention described herein may be manufactured and used by or for the Government for governmental purposes, without the payment to me of any royalty thereon.

5 The invention relates to preventative medicine, more particularly it is directed to the control of venereal diseases, through the use of a chemical prophylaxis which if applied immediately after exposure will destroy the infecting agents and 10 thus prevent the invasion of the tissues and consequent development of the disease.

The United States Army in its efforts to control venereal diseases, such as syphilis, gonorrhea and chancroid (soft chancre) has depended largely 15 upon the establishment of venereal prophylactic stations. Individuals reporting to these stations are given a prophylactic treatment consisting essentially of an external genital anointment with a 1-1000 solution of mercuric chloride, followed 20 with a urethral injection of from four to six cc. of a two percent solution of protargol, argyrol or similar germicide.

This method of venereal control has proved highly effective, when treatment has been administered before the organisms invade the tissues, but any delay, which intervenes between exposure 25 and the application of the prophylactic, serves to proportionally decrease the chances that the prophylactic will prevent infection and it is this 30 time factor which constitutes the weak phase in the prophylactic station control.

All too frequently the remoteness of the station or procrastination delays application for treatment until the effective period has elapsed, with 35 the result that the administration of the prophylactic comes too late.

It is therefore the aim and purpose of this invention to eliminate the prophylactic station with its requirement for specially trained personnel 40 and expensive administrative equipment and substitute a venereal control, in the nature of a prophylactic composed essentially of soap, and a suitable base; the prophylactic being self administered to permit application immediately after 45 exposure and thus remove one of the most serious defects associated with the present method for venereal control.

Before selecting the prophylactic comprising the 50 subject matter of this application an investigating unit of the Army experimented with the prophylactic described and claimed in my co-pending application Serial Number 557,747, filed August 17, 1931, which briefly stated comprised a bougie composed of 30 parts gelatin, 20 parts glycerin, 1 55 part soap and 100 parts water. This type of pro-

phylactic was satisfactory from the standpoint of its germicidal properties but was objectionable to the extent that it did not adequately provide for external anointment of the genitals and its use was sometimes accompanied with considerable 5 pain. To remove these objectionable features, the bougie has been replaced by the instant preparation which is prepared in the form of a paste adapted to be distributed in one dram collapsible tubes, one half of the contents of the tube to be 10 employed to externally treat the genitals and the remaining portion to be utilized for injection in the urethral tract.

Another object of this invention is to provide 15 a prophylactic agent in the nature of a water soluble paste which after going into solution with the glandular excretions of the urethral canal will readily penetrate the lacunae of the urethra; that is to say the little recesses in the mucus membrane of the tract into which empty the ducts of 20 the urethral glands and wherein frequently lurk the infected organisms to be destroyed.

With these and other objects in view, this invention consists in certain novel details with respect to the mode of preparation and amounts of 25 ingredients to be more particularly hereinafter set forth and claimed.

The problem of a suitable dependable prophylactic to replace the present method of venereal control has occupied the attention of the Army 30 medical investigators for several years, as they have realized that the tendency of human nature to procrastinate injected a serious defect in any venereal control which involved more or less of a journey from the place of exposure to the prophylactic station. They also appreciated the fact, than any substitute, relying upon self administration must be simple in application and effective with respect to three distinct types of 35 infection.

This requirement of a prophylactic equally effective against the poisons of syphilis, gonorrhea and chancroid made it necessary to disregard the well known venereal germicides and led to experimentation with soaps which were recognized 45 as weak disinfectants. After considerable laboratory experimentation, a pure neutral soap, such as castile was found to be best suited to the purpose. Even pure castile soap, however, if too strong, was found to be more or less irritating to 50 the membranes of the urethral canal.

This observation led to tests of castile soap in various strengths above that known to be necessary to kill the invading micro-organisms, and in carrying out these tests, pure castile soap to the 55

- strength of 1-100 was applied to a highly inflamed urethra without any indications of discomfort. These results gave rise to the conclusion that if pure castile soap of a strength of 1-100 killed the organisms responsible for syphilis, gonorrhea and chancroid in about 2½ minutes and did not irritate even a highly sensitive urethra, then this would be the ideal strength for the germicide in the prophylactic.
- 10 The next factor considered in the solution of prophylactic problems was the choice of a carrier for the germicide, which would bring the latter into intimate contact with the organisms to be destroyed.
- 15 The selected germicide, pure castile soap, being water soluble, it was decided the most desirable base would be one having this same characteristic, so that when the germicide and base both went into solution with the glandular excretions 20 of the urethral canal, the prophylactic would not only bathe the wall of the canal but would also penetrate the lacunae of the urethra, thus reaching the places where the poison germs sometime lurk. To this end a base was selected consisting 25 of tragacanth, corn starch, glycerine and water.
- Having determined the most effective germicide, its strength, and the base, the following formula was derived:
30 Pure castile soap	grams	1
Tragacanth	do	.230
Corn starch	do	5
Glycerine	c. c.	90
Water	c. c.	10

To prepare the prophylactic from the preceding formula, the soap, tragacanth, corn starch and glycerine are dissolved in 10 c. c. of water, the mixture heated to 140° C. After the mass has 40 been allowed to cool the resulting paste is placed in a one dram collapsible tube for distribution. To aid in the administration of the prophylactic, the distributing tubes are preferably formed with extended nozzles suitably dimensioned for easy insertion into the urethra, as 45

will be readily understood without further discussion.

In conclusion it may be stated, tests made with this prophylactic have demonstrated that as a venereal control it is inexpensive, simple in administration and apparently highly protective and equally effective with respect to syphilis, gonorrhea and chancroid.

Having described my invention, what I claim as new and wish to secure by Letters Patent is:

1. A venereal prophylactic comprising a soap, the strength of the latter being sufficiently effective as an injection and unguent against the micro-organisms responsible for syphilis, gonorrhea and chancroid, but non-irritating to the surface treated, and a hygroscopic and cell stimulating base adapted to carry the soap into intimate contact with the invading organisms, said base including glycerine and water, the soap and base being soluble in the glandular secretions of the urethral canal.

2. A venereal prophylactic comprising a soap, the strength of the latter being approximately 1-100th, but sufficient to be equally effective against the micro-organisms responsible for syphilis, gonorrhea and chancroid, but non-irritating to the surface treated, and a hygroscopic and cell stimulating base to carry the soap into intimate contact with the invading organisms, the soap and base being soluble in the glandular secretions of the urethral canal, said base comprising tragacanth, corn starch, glycerine and water.

3. A venereal prophylactic comprising a soap of a strength sufficient to be equally effective as an injection and as an unguent against the micro-organisms responsible for syphilis, gonorrhea and chancroid, but non-irritating to the surface treated, and a base including a hygroscopic agent adapted to stimulate the cells of the urethral tract whereby to produce an abundant solvent so that the soap and base going into solution with the solvent will be carried into intimate contact with the invading micro-organisms.

SEWELL M. CORBETT. 45
